CLAIM

The ornamental design for a camera covering, as shown and described.

DESCRIPTION

Reference is made to commonly assigned, co-pending U.S. patent application Ser. No. 29/153,025 entitled CAMERA WITH INTEGRAL FLASH FEATURE, filed Dec. 21, 2001, in the names of Anna C. Schelling, Robert J. Stanchus, Thomas E. Dussinger, and Anthony F. DiGaetano; U.S. patent application Ser. No. 29/153,026 entitled CAMERA WITH INTEGRAL FLASH FEATURE, filed Dec. 21, 2001, in the names of Anna C. Schelling, Robert J. Stanchus, Thomas E. Dussinger, and Anthony F. DiGaetano.

FIG. 1 is a front view of the camera covering according to our new design;

FIG. 2 is a left side view thereof;

FIG. 3 is a right side view thereof;

FIG. 4 is a top view thereof;

FIG. 5 is a bottom view thereof; and,

FIG. 6 is a perspective view of a camera covering installed on a camera rear portion, the broken line showing of a camera is shown to illustrate environment only and forms no part of the claimed design.
